UNITED STATES PATENT OFFICE.

FRANK C. LOCKE, OF MARSHALL, MICHIGAN, ASSIGNOR TO WILLIAM C. SHERER AND SAMUEL J. SHERER, BOTH OF CHICAGO, ILLINOIS.

DISPLAY-COUNTER.

1,159,336.

Specification of Letters Patent.

Patented Nov. 2, 1915.

Application filed August 12, 1914. Serial No. 856,345.

To all whom it may concern:

Be it known that I, FRANK C. LOCKE, a citizen of the United States, residing at Marshall, in the county of Calhoun and 5 State of Michigan, have invented a certain new and useful Improvement in Display-Counters, of which the following is a specification.

My invention relates to improvements in 10 display counters and has for its object to provide convenient means whereby each pocket can be easily inserted and will be positively and fixedly secured in position by the act of insertion.

15 The invention is illustrated in the accompanying drawings, wherein—

Figure 1 is a side elevation of such pocket; Fig. 2 is a side elevation of such pocket and vertical section through a portion 20 of the counter showing the pocket in the process of being inserted; Fig. 3 is a similar elevation in vertical section showing the pocket in position; and Fig. 4 is a cross section on the line 4—4 of Fig. 3.

25 Like parts are indicated by the same letter in all the figures.

A is the front frame of the pocket and B, B the side walls. These side walls have each grooves C, C for the adjustable partition 30 D, and E for the glass plate F which lies immediately back of the front frame and exposes the contents of the pocket. The grooves C, C and E are carried across or formed in the upper surface of the bottom 35 G of the pocket. The upper portion of the front frame of the pocket extends quite a considerable distance above the upper portion of the side, and near the middle of each side of the pocket is secured the projecting 40 pin J. K is the frame of the counter which is shaped so as to leave a proper opening for the reception of the pocket. The vertical length of this opening is considerably greater than the vertical length of the side 45 frame pieces of the pocket.

On the inner surfaces of these frame pieces K about the opening are secured lock strips L, the main body of each of which is approximately the same width as the distance 50 between the side of the pin J, and the rear face of the pocket frame. The upper

portion of each lock strip is preferably slightly wedge-shaped as at M and the length of the lock strip is considerably greater than the distance from the pin J to 55 the lower end of the side frame of the pocket.

I do not wish to be limited to the precise structure, form and arrangement of these several parts, as, of course, they could be 60 modified without departing from the spirit of my invention.

The use and operation of my invention is as follows: With a counter having a structure such as shown and a pocket such as 65 illustrated, the pocket can be inserted in the opening in the manner indicated in Fig. 2, that is, by pushing the pocket into the upper part of the opening and then swinging it in until the pins J pass over the tops of 70 the lock strips, then bringing the inner face of the front frame of the pocket flush against the side of the counter and then dropping the pocket down into the position indicated in Fig. 3. By this means the 75 pocket is held midway its vertical length and wedged or at least firmly secured in this position so that the pocket will not tend to shift laterally or vertically and will not tend to swing outward at either end so as to 80 admit foreign substances. The slight wedging effect may be dispensed with and for most purposes the pocket will be sufficiently 85 securely held in position, but any device which tends to yieldingly hold or force the pocket into fixed position may be employed such as the wedge or any substitute therefor.

I claim:

1. A display counter having an opening in combination with a display pocket to fit 90 therein, said pocket comprising a frame, a body on the frame and pins approximately midway along the sides of the body, said opening longer than the pocket body and provided with vertical ribs near its front, 95 the distance from the top of the ribs to the bottom of the opening being longer than the distance from the pin to the bottom of the body, the upper portions of said ribs slightly wedge-shaped.

2. A display counter having an opening in combination with a display pocket adapt-

ed to fit therein, the height of the display pocket being less than the height of the opening, a fixed holding member located within the opening, a holding member 5 mounted on the pocket for engagement with the fixed holding member when the pocket is moved vertically in the opening.

In testimony whereof, I affix my signature in the presence of two witnesses this third day of August 1914.

FRANK C. LOCKE.
